PISTON SKIRT EXPANDER

Charles A. Marien and Melvin W. Marien, St. Louis, Mo., assignors to Ramsey Accessories Manufacturing Corporation, St. Louis, Mo., a corporation of Missouri

Application November 19, 1941, Serial No. 419,704

9 Claims. (Cl. 309—12)

Our invention has relation to improvements in expansion and tensioning devices for pistons, which devices are commonly called piston skirt expanders, and it consists of the novel features of construction more fully set forth in the specification and pointed out in the claims.

The present invention is an improvement over that shown in Patent No. 2,198,829 granted to Charles A. Marien on April 30, 1940. It has the same objects as those embodied in said patent, namely, the expanding and reshaping of a deformed piston skirt and exerting pressure on the inside of said skirt along an axis at right angles to the axis of the piston bosses; but in addition thereto it is so constructed that it may be more easily handled while being inserted into the skirt or removed therefrom.

A further object of the present improvement is the embodying in the expander of means whereby the supporting members for the expander are rigidly held against pivotal movement throughout the rapid reciprocating action of the piston while in use.

These features as well as others inherent in the invention will be better apparent from a detailed description of the same in connection with the accompanying drawings, in which:

Figure 1 is a combination side elevation and middle vertical section taken through a conventional type of piston showing our improved skirt expander carried by the piston pin and exerting its tension on the lower part of the piston skirt; Fig. 2 is a bottom plan of the piston showing the skirt expander secured therein; Fig. 3 is a vertical longitudinal section taken through the piston skirt on a plane indicated by the line 3—3 of Fig. 1; Fig. 4 is a top plan view of my improved expander showing both the expanded position when not inserted in the piston skirt and the operative position when confined within the piston skirt and exerting its pressure thereagainst (the latter position being dotted); Fig. 5 is a middle vertical longitudinal section taken on the line 5—5 of Fig. 4; Fig. 6 is a combined side elevation and vertical longitudinal section of a piston skirt showing a somewhat different form of skirt expander which has been dislodged from its initial position through the force of inertia and of the impact of the explosions during the operation of the engine; (this view is for comparison only with Fig. 1); Fig. 7 is a plan view of a modified form of the invention in which the ends of the spring member are held together by a clip prior to the insertion of the expander in a piston, one of the supporting lugs of the

expander having been removed; Fig. 8 is a side elevation thereof; Fig. 9 is a vertical longitudinal section taken on the line 9—9 of Fig. 7; and Fig. 10 is a cross-sectional detail taken on the line 10—10 of Fig. 8.

Referring to the drawings, P represents a piston of a typical construction having the usual pin bosses 1, 1 for supporting a piston pin 2 which holds the connecting rod 3 and the piston P in operative relation.

As stated above, after the piston P has been in use for some time, the skirt portion thereof wears and often becomes distorted so that it no longer fits properly in the engine cylinder. When this condition becomes severe, the piston must either be replaced or restored to its proper shape. In the majority of instances the wear is not sufficiently severe to require replacement of the piston, but the latter may be reshaped and provided with a skirt expander as illustrated in Figs. 1 to 4 inclusive. In the present improvement the skirt expander embodies an annular spring member 4 (preferably in the shape of an elongated oval) having parallel sides 5, 5', 5" and arcuate end portions 6, 6' which constitute the expanding parts of the expander. The side portions 5, 5', 5" are separated by a gap 7 and have their ends bent outwardly at right angles to provide fingers 7, 7' which may be gripped by an appropriate tool for the purpose of contracting the spring member 4 as a whole whereby it may readily be inserted or removed from the skirt S of the piston.

When the spring member 4 is in its relaxed condition (that is, not under tension within the piston skirt) its length from one end to the other is greater than the inside diameter of the piston skirt so that, after being contracted and inserted within the skirt, it exerts considerable force outwardly on said skirt at diametrically opposite points in the direction at right angles to the axis of the pin bosses. This of course imparts a somewhat cam-shape to the piston skirt and approximates its original shape before having become distorted through use.

Obviously the force with which the spring member 4 bears against the inner surface of the piston skirt is insufficient to hold the spring member in place during the operation of the piston so that means must be provided for securely anchoring the spring member within the piston. As in Patent No. 2,198,829 we provide a pair of sheet metal supporting ears 8, 8' which have perforated lobes 9, 9' at their upper ends and extended channel-shaped formations 10, 10'

at their lower ends. The channels 10, 10' are provided with crimped retaining portions 11, 11', whereby the sides 5, 5', 5', of the spring member 4 are securely held in assembly relation with the supporting ears 8, 8'. The outwardly presented wall 12' of channel 10' is provided with an opening 13 through which the extremities 7, 7 of spring member 4 project (Figs. 1 and 4). As may be seen in Fig. 2, the ears 8, 8' are confined between bosses 1, 1 and connecting rod 3 and the channel members 10, 10' are of a length that they fit snugly between opposite portions of piston skirt S so that when the skirt expander is mounted within the piston skirt it is securely held in place so that there is no possibility of its working loose or tilting under the forces to which it is subjected when the piston is in operation. Furthermore the spring member 4 bears with a slight pressure against the inner surface of channel abutment members 10, 10' insuring that the ends of these members will be held in intimate contact with the piston wall. Even if the spring member 4 should break because of the severe action to which it is subjected and thus become detached from the supporting ears 8, 8', the latter will still be unable to work loose as they are confined in one direction between bosses 1, 1 and connecting rod 3 and they are confined in a direction at right angles thereto by contact of the piston skirt with the ends of channel members 10, 10'.

If it were not for the contact of the channel members 10, 10' with opposite portions of the piston skirt, spring member 4 might under certain conditions work loose and slide through the channels 21 of supporting ears 20 and become dislodged as shown in Fig. 6, under the hammering action to which the piston is subjected during the operation of the engine, as alluded to above.

From the foregoing it is apparent that the extended portions 10, 10' of the supporting ears 8, 8' not only securely hold the spring member 4 within the piston skirt S but are themselves confined within said skirt in such a manner that they cannot be subjected to pivotal motion which would permit the expander to tip as shown in Fig. 6. Our improved expander also has the advantage over similar types of expanders as heretofore made in that the placing of the gap 9 in the side of the spring member 4 instead of in the end permits of greater contraction of the spring element, and of course consequently greater tension upon the piston skirt at diametrically opposite points when inserted therein.

In the modification shown in Figs. 7 to 10 inclusive, spring member 22 is held in assembled relation with supporting ear 23 by bead 24 formed on the edge of bottom wall 25 of channel 26. Furthermore in this modification the ends 22', 22' of spring 22 do not have outwardly extending fingers as in the form shown in Figs. 1 to 5 inclusive, as these ends are held together for the purpose of contracting the spring member 22 by a U-shaped clip 27, the ends 28, 28 of which are disposed in grooves 29, 29 formed in the upper surface of spring member 22 in close proximity to each end thereof.

The clip 27 serves to hold the spring 22 in contracted position until the expander has been positioned within the piston after which the clip 27 is removed and the spring member 22 thus

allowed to exert its tension at diametrically opposite points against the piston skirt.

Having described our invention, we claim:

1. A piston skirt expander comprising an expanding element having side members and piston skirt engaging members, a supporting element secured to each of said side members, and extended abutment portions on the supporting elements.
- 10 2. A piston skirt expander comprising an expanding element having side members and piston skirt engaging members, a supporting element secured to each of said side members, each of the supporting elements having elongated channel parts embracing and extending beyond a side member of the expanding element.
- 20 3. A piston skirt expander comprising a spring element of the general shape of an elongated oval having a gap in one side thereof and outwardly projecting fingers adjacent to said gap, and a supporting element secured to each side of said spring element, one of said supporting elements being recessed to permit the projecting fingers to extend therethrough.
- 25 4. A piston skirt expander comprising a spring element of the general shape of an elongated oval having a gap in one side thereof, a supporting element secured to each side of said spring element, and extended abutment portions on the supporting elements.
- 30 5. In combination with a piston having a skirt and piston pin bosses for the reception of a piston pin, a piston skirt expander comprising a spring element having side members and skirt engaging members, a supporting element secured to each of said side members, each supporting element having a perforated lobe for receiving the piston pin and an extended portion for engagement with the inside of the piston skirt.
- 35 6. A piston skirt expander comprising a spring element of the general shape of an oval having a gap in one long side thereof and the opposite side serving as a spring exerting tension along the long axis of the oval, and means for securing the expander in a piston skirt.
- 40 7. A piston skirt expander comprising a spring element of the general shape of an oval having a gap in one long side thereof and the opposite side serving as a spring exerting tension along the long axis of the oval, and oppositely disposed supporting ears connected to said spring element.
- 45 8. A piston skirt expander comprising a spring element of the general shape of an oval having a gap in one long side thereof and the opposite side serving as a spring exerting tension along the long axis of the oval, and a supporting ear secured to each of said sides of the spring element, each of said supporting ears having abutment portions coextensive with said longitudinal axis.
- 50 9. A piston skirt expander comprising a spring element of the general shape of an oval having a gap in one side and the opposite side serving as a spring exerting tension along the long axis of the oval, means engaging the spring element adjacent to each side of the gap for holding the spring element in contracted position, and means for securing the expander in a piston skirt.
